UNITED STATES PATENT OFFICE.

GEORGE A. BURNHAM, OF SAUGUS, MASSACHUSETTS, ASSIGNOR, BY MESNE ASSIGNMENTS, TO CONDIT ELECTRICAL MANUFACTURING COMPANY, A CORPORATION OF MASSACHUSETTS.

ELECTRIC SWITCH.

Application filed February 17, 1921. Serial No. 445,757.

To all whom it may concern:

Be it known that I, GEORGE A. BURNHAM, a citizen of the United States, residing at Saugus, in the county of Essex and State 5 of Massachusetts, have invented an Improvement in Electric Switches, of which the following is a specification.

This invention relates to electric switches adapted to carry and interrupt relatively 10 high values of current.

In the normal type of switch having stationary switch members and a movable brush-member, it is found that currents of relatively high value tend to force the brush 15 laminæ outwardly away from contact with the stationary switch members and thereby reduce the contact pressure and consequently the current-carrying capacity of the switch. Due to the alternating magnetic 20 effect, the brush laminæ tend to vibrate and arcing may occur which will burn the contact faces and reduce the current-carrying capacity.

An object of this invention is to provide 25 an electric switch with movable and stationary contact members so arranged that they will not tend to separate when carrying currents of high value, and may even tend to press more firmly together, thereby 30 to increase the contact pressure and the current-carrying capacity of the switch.

In carrying out this object of the invention, I may provide the stationary switch members with brush members so arranged 35 that the toes or contact faces thereof are directed inwardly toward each other; and I may employ some form of movable switch member other than a brush member for the bridging member. With this arrangement, 40 the magnetic effect of the current tends to move the brush laminæ in the same direction as before, or outwardly, but due to the relatively reversed angle of the toes of the brush members, the laminæ are now 45 caused to press with greater force against the cooperating contact-member, and consequently the current-carrying capacity of the switch is not reduced and may even be enhanced by the magnetic effect of currents 50 of high values.

The current-carrying capacity of an electric switch is limited by the rise in temperature of the conducting components re-

sulting from the current carried by them.

A considerable amount of heat is developed 55 at the junction of the stationary and movable switch-members, due to the contact resistance. The heat is conducted into the stationary switch members and brush member and is finally dissipated, but the contact 60 junction, and the brush member in particular, will be relatively highly heated in comparison with other conducting components of the switch.

A further object of this invention is to 65 provide an electric switch having means to dissipate the heat generated at the contact junction and thereby lower the temperature rise of the contact-members and increase the current-carrying capacity of the switch. 70

In carrying out this object of the invention, I may employ a brush-member as one contact-member and a co-operating contact-member having a slotted or grooved contact face arranged to provide a plurality of conducting bars with intermediate oil passages. Due to this arrangement the bars act to dissipate rapidly the heat generated at the contact junction, and by reason of its good mechanical contact with the brush-member, when the switch is closed, said bars serve to abstract and dissipate heat from the brush-member. Furthermore, oil has access directly to the contact 80 face of the brush member and will cool it. 85

The current-interrupting capacity of an electric switch has some dependence upon the speed at which the circuit is interrupted and, other things being equal, that switch having the greater speed of movement of the movable switch member to open position will have the greater current-interrupting capacity. The solid bar or brush member which has heretofore comprised the bridging member of the movable switch member presents a substantial surface to the oil in switch-opening movement and consequently the oil appreciably retarded the speed of switch-opening movement. 90 95

A further object of this invention is the provision of a movable switch member adapted to offer a reduced resistance to switch-opening movement through the oil. 100

A switch embodying this object of the invention may have its bridging-member formed with a plurality of oil passages 105

therethrough arranged in the direction of movement of the said bridging-member whereby to present reduced surface to be acted upon by the oil and facilitate the speed of movement of the switch-member. The bridging member may be constructed of a plurality of bars placed on edge with oil spaces therebetween and adapted to engage the stationary switch-member in edge-wise order. The bridging-member thus arranged serves to abstract heat from the contact junction and in addition to being kept cool by provision of the oil passages, serves to keep the stationary contact members cool.

15 A further object is to provide the novel features above set forth as an attachment to certain existing forms of switches.

16 A further object is generally to improve the construction and operation of an electric switch.

Fig. 1 is a side elevation in section of an oil immersed electric switch embodying my invention.

25 Fig. 2 is a sectional view, along lines of 2—2 of Fig. 3, of the bridging member.

Fig. 3 is a plan view of the bridging member of Fig. 2.

30 Fig. 4 is a detail of the stationary brush-members and bridging-members in the open position of the switch.

Fig. 5 is a section of the bridging-member along line 5—5 of Fig. 2.

Fig. 6 is a sectional detail of a stationary brush-member.

35 Fig. 7 is an end view of the brush-member of Fig. 6.

Fig. 8 is a perspective view of the brush-member holder.

40 Fig. 9 is a detail of a modified form of stationary-contact-member and removable brush-member.

Fig. 10 is an end view of the stationary contact member of Fig. 9.

45 Fig. 11 is a detail of the end of a modified form of stationary contact-member.

Fig. 12 is a sectional detail of the contact member of Fig. 11.

50 As here shown my invention is embodied in the switch including the frame 10 from which the oil receptacle 11 is removably dependent. Stationary switch-members are carried by said frame and include the insulators 12 through which the rods or switch-studs are extended and the relatively 55 massive blocks 14 secured to the lower ends of said rods. In the usual type of oil immersed switch said blocks 14 form the contact blocks or members adapted to be engaged by the movable switch-member, which includes a brush-member as the bridging member. In the switch embodying this invention, however, I may utilize said blocks to carry and support stationary brush-members and utilize other than a brush-member as the bridging member. Said brush-members

70 75 80 85 90 95 100

15 are formed of a plurality of laminae assembled to form the shank-portions 15^a and the downwardly reflexed end portions or toes 15^b terminating in the contact faces 15^c. While the brush-members may be secured to the contact blocks 14 or, if desired, directly to the studs 13 of the stationary switch-members, in any suitable manner, I find that unless care is exercised in design of the securing means, certain laminae of the brush-members may be forced to carry an excessive amount of current and may become excessively heated. I find that very good results are obtained by enclosing the shanks 15^a of the brush-members in the brush-holders 16, illustrated more particularly in Fig. 8. Each holder is formed preferably of a single sheet of copper or equivalent reflexed to form the side members 16^a and top members 16^b which enclose and grip the shank-portions of the brush-member. An extension is reflexed to form a shoulder 16^c against which the ends of the laminae of the brush-member abut.

90 95 100

A brazing metal, or solder, is run into the interstices between the brush-member and holder so that both are mechanically and electrically connected. The side portions 16^a of the holder serve to conduct current from the side-edges and the shoulder 16^c from the end edges of each lamina of the brush-members so that each lamina carries mainly but its just proportion of the total current carried by the switch and consequently no portion of the shank of the brush-member is likely to become independently excessively heated.

100 105 110

Said holder is formed with the ears 16^d having screw openings through which screws 17 are passed and removably threaded into said blocks 14 by which said brush-members are secured to said blocks.

110 115 120

A stationary auxiliary contact-member is carried by each brush-member. Said contact-member is of U-shape and has the contact face 18 and the ears 18^a which straddle the brush-holder and through which screws 19 are passed to secure it removably to the brush holder.

11 12 125

Said brush-members are removably secured to the lower faces of said blocks 14 and the arrangement is such the brush-members and the movable switch-members hereinafter to be described may be applied to existing switch-structures, if desired, by securing the stationary brush-members to the stationary contact members and substituting the new bridging member for the removable brush-member.

12 13 135

The stationary brush-members are applied to the switch-studs so that their toes 15 are inwardly directed toward each other and the contact faces are in the same plane for engagement with the movable switch-member.

The movable switch-member includes the

insulating rod 20 to the lower end of which which latter they are removably secured. the movable contact or bridging member is carried. A rod 21 is secured to the upper end of said rod 20 and extends through an opening in the switch frame and is connected with switch operating mechanism 22, which latter is or may be of more or less usual construction.

A movable contact or bridging member 10 arranged to provide increased cooling effect of the contact faces of the movable and stationary switch-members, and thereby increased current-carrying capacity; and increased speed of opening; and thereby increased current-interrupting capacity of the switch is an object of this invention.

The movable contact or bridging-member is herein shown as formed of a plurality of relatively thin and wide bars arranged on edge in a supporting member and spaced apart to provide oil passages 23^a therebetween. This structure is illustrated more particularly in Fig. 3. The top edges of said bars are adapted to engage the contact faces 25 of the stationary brush-members. Inasmuch as the bars are relatively thin and are surrounded by oil, heat generated at the junction of said bars and brush-member is rapidly dissipated so that the temperature 30 rise at the junction is kept down to a low value.

While the actual mass of copper of the bridging-member is or may less than that of a solid member, yet by reason of the laminated structure and the enhanced cooling effect, the current-carrying capacity of the member may be increased.

Due to the spaced relation of the bars comprising the bridging member the superficial area presented to the oil, when the switch is moved toward open position, is considerably less than that which would be presented by a solid bar having the same overall dimensions and consequently the speed of the member to open position and consequently the current-interrupting capacity of the switch may be increased.

The number of bars employed will vary in accordance with the value of current to be controlled by the switch.

Said bars 23 are carried by the supporting members having the two arms 24 and the intermediate portion 24^a. The insulating rod 20 is received between said arms and is secured thereto by the pin 25 to permit the self-aligning of the bridging-member with the stationary switch-members. Said bars 23 are also arranged to be independently self-aligning on said stationary switch-members. For this purpose each of said bars has the two holes 23^b formed therein on opposite sides of its vertical median line, and pins 26 of smaller diameter than said holes are extended therethrough and through 65 said arms 24 of the supporting member, in

Spacing washers 27 are disposed on said pins between the bars to preserve proper spacing therebetween. This arrangement is such that if, for instance, the top edge of 70 a bar extends above the edges of adjacent bars, said bar will rock about one or the other of said pins 26, when moved into contact with the stationary switch-members, and the high end of the bar will be depressed 75 and the low end of the bar raised until both ends of the bar are in contact with both stationary switch-members.

The arrangement of the bridging member also is such that the bars 23 may be turned 80 edge for edge to present fresh contact faces when the first used faces have become rough or burned, and the effective life of the bridging member may thereby be doubled.

The auxiliary movable contact members 85 are supported in housings 28 beyond the ends of the bars 23 by the bars 29 disposed on edge and secured to the outer faces of the arms 24 of the bridging-member supporting frame. The contact-member housings are formed of strip material reflexed to form a rectangular structure having top and bottom wells aligned openings therein and side walls through which screws 30 are passed and threaded into the bars 29. 95 Auxiliary contact members comprising the cylindrical rods 31 are slidably received in said openings and springs 32 encircling them admit of their yielding when in contact with the stationary auxiliary contact 100 members to admit further movement of the movable switch-members in switch-closing direction. A flexible conductor 33 is extended between said contact members and connected thereto by the screws 34; and 105 said conductor may also be secured to the bridging-member frame by the screws 35.

That feature of the invention wherein the junction between the movable and stationary switch-members is cooled may be also accomplished by providing the stationary contact members, instead of the movable contact-members, with oil passages in its contact faces. This modification is illustrated in Figs. 9 through 12.

As illustrated in Figs. 9 and 10 the usual form of brush-member 40 and auxiliary contact-member 41 for the bridging-member is employed. The stationary contact-member, in this case, is or may be formed with alternate conducting-portions and oil channels arranged transversely of the laminae of the brush-member. The stationary contact-member may comprise the block 42 having slots in its lower face in which the bars 43 120 are inserted and secured in any suitable manner. The lower edges of said bars are adapted to be engaged by the brush-members and the spaces or channels 44 between said bars provide for the circulation of oil 125

about the bars whereby heat generated at the contact surface is dissipated.

It should be noted that, with this construction, the brush-member itself is cooled by reason of the spaced relation of the bars contacting therewith whereby to admit cooling oil to the contact faces thereof, and by reason of the increased cooling effect, it may carry an increased current for the same 10 temperature rise.

The stationary auxiliary contact-members may comprise the U-shaped members 45 disposed over the bars 44 and secured removably to said blocks 42 by the screws 46.

15 The contact block 42 may be cut to form the alternate spaced conducting and heat dissipating bars 42 and oil channels 44, as illustrated in Figs. 11 and 12 if desired.

It is obvious that the structure herein disclosed may be otherwise modified without departing from the spirit of the invention.

I claim:

1. An electric switch having a contact-member formed with a plurality of circulating passages for a cooling medium in its contact face.

2. An electric switch having a contact-member formed with a plurality of relatively deep and narrow circulating passages 30 for cooling in its contact face through which oil is adapted to pass to cool the contact member.

3. An electric switch having a contact-member formed of a plurality of conducting components arranged to present a contact-face for said member and circulating passages for a cooling medium between them extended inwardly from the contact face by which to admit of the cooling of said conducting components.

4. A contact-member for an electric switch having a plurality of edge-wise arranged bars co-operating to form a contact-face for said contact-member and spaced apart to provide a plurality of passages between them extended inwardly from the contact face to admit of the circulation of a cooling medium therethrough for the cooling of said contact-member.

5. An electric switch having two relatively movable contact-members each having co-operating contact-faces, one of said contact-members arranged to admit of the circulation of a cooling medium over portions of the contact face of said other contact-member when said members are in contact.

6. A contact-member for an electric switch having a contact face and means to dissipate heat generated at its contact face comprising a plurality of passages in said member extended below the contact face through which a cooling medium is adapted to circulate.

7. An electric switch having a brush-mem-

ber and a co-operating contact member, said contact-member having a plurality of laminae arranged transversely of the laminae of the brush-members and spaced apart to provide passages through which a cooling medium is adapted to circulate.

8. An electric switch having a brush-member and a co-operating contact-member, said contact-member having a plurality of laminae arranged transversely of the laminae of the brush-members and spaced apart to provide passages through which a cooling medium is adapted to circulate and contact with said brush-member and contact-member to cool both.

9. An electric switch having stationary switch-members including brush-members and a movable switch-member including a plurality of laminae arranged transversely of the laminae of said brush-members and spaced apart to provide passages through which a fluid is adapted to circulate.

10. An oil immersed electric switch having stationary switch-members and a bridging-member having a plurality of edgewise-arranged conducting bars adapted to make edgewise contact with said stationary switch-members and spaced apart to admit of passage of oil therebetween.

11. An oil immersed electric switch having stationary switch-members and a movable switch member comprising a plurality of spaced bars having oil passages between them, whereby to increase the speed of switch-opening movement of said movable switch-member.

12. An oil immersed switch having stationary switch-members and a movable switch-member comprising a plurality of bridging bars spaced to provide oil passages therebetween extended in the direction of movement of said movable switch member.

13. An electric switch comprising stationary switch-members and a movable switch-member including a plurality of spaced-apart edgewise arranged bars adapted to engage said stationary switch-members, and auxiliary contact members disposed beyond the ends of said bars.

14. An electric switch comprising stationary switch-members and a movable switch member including a supporting frame, a plurality of spaced apart, edgewise arranged bars extended on both sides beyond said frame, and means connecting said bars with said frame which admits of the aligning of the contact-faces of said bars in said frame.

15. An electric switch having a movable switch-member including a plurality of closely-spaced, edgewise-arranged bars, a supporting frame in which said bars are secured, said bars having two sets of aligned holes therethrough and pins of smaller diameter than said holes passed through the two sets of holes and secured in said frame.

whereby to admit of the rocking of said bars independently upon one or the other of said pins.

16. An electric switch including a fixed contact member having a contact face, a movable bridging-member including a supporting frame, and a plurality of closely-spaced edgewise-arranged bars removably secured in said frame and all arranged to engage the contact face of said fixed contact member.

17. An electric switch having a movable switch-member including a supporting-frame, and a plurality of closely-spaced edgewise-arranged bars removably secured reversibly in said frame.

18. An electric switch including a fixed contact member having a contact face, a movable bridging-member including a supporting-frame, a plurality of bars all arranged to engage the contact face of said fixed contact member, and means pivotally supporting said bars in closely-spaced, edgewise order in said frame.

19. In an electric switch, a stationary switch-member including a laminated brush-member having a shank portion and an angularly inclined toe-portion terminating in a contact-face, and a brush-holder having side portions adapted to engage the sides of the laminae and a shoulder adapted to engage the ends of the laminae in the shank-portion to conduct current therefrom.

20. In an electric switch, a stationary switch-member including a switch-stud, a laminated brush-member having a shank-portion and an angularly inclined toe-portion terminating in a contact face, and a brush-holder having side portions adapted to engage the side of the laminae and a shoulder adapted to engage the ends of the laminae in the shank-portion to conduct current therefrom and means removably to secure the holder to said switch-stud.

21. An electric switch comprising a fixed pair of brush members, and a movable bridging-member comprising a plurality of bars each adapted to engage said pair of

brush members, and a switch rod carrying 50 said bars.

22. An electric switch comprising a fixed pair of brush members, and a movable bridging-member comprising a plurality of bars each adapted to engage said pair of 55 brush members, and a switch rod carrying said bars having supporting means for said bars by which each bar is adapted for independent pivotal movement.

23. An electric switch comprising a fixed 60 pair of inverted brush members and a movable bridging-member comprising a plurality of spaced bars adapted to be raised to engage and bridge said pair of brush members, and a switch rod carrying said bars. 65

24. An electric switch having fixed contact members, and a bridging-member adapted to bridge and connect said fixed contact members, said bridging member formed of a plurality of bars adapted to 70 bridge and make independent edgewise contact with said contact members.

25. An electric switch having the combination of a laminated fixed contact member, a laminated movable contact member 74 for said fixed contact member, and means to effect the engagement of said contact members with the laminations thereof angularly disposed to each other.

26. An electric switch having the combination of laminated fixed contact members, and a laminated movable bridging-member for said fixed contact members, the laminations of said bridging member being angularly disposed to the laminations of said 85 fixed contact members.

27. In an electric switch, a stationary switch-member including a laminated brush-member having a shank portion and an angularly inclined toe-portion terminating in 90 a contact-face and a brush-holder having side portions maintained in pressure-contact and electrical engagement with the sides of the laminae.

In testimony whereof, I have signed my 95 name to this specification.

GEORGE A. BURNHAM.
